United States Patent Office.

WILLIAM COOPER, OF DEPOSIT, NEW YORK.

Letters Patent No. 73,080, dated January 7, 1868.

IMPROVEMENT IN MELODEONS.

The Schedule referred to in these Letters Patent and making part of the same.

TO ALL WHOM IT MAY CONCERN:

Be it known that I, WILLIAM COOPER, of Deposit, in the county of Broome, and State of New York, have invented certain new and useful Improvements in Melodeons and other reed-instruments of similar character; and I do hereby declare that the following is a full, clear, and exact description of the same, reference being had to the accompanying drawings, making a portion of this specification, in which—

Figure 1 is a vertical transverse section of a reed-instrument constructed according to my invention.

Figure 2 is a front view of the same.

Similar letters of reference indicate corresponding parts in both figures.

One of the defects which exist in all melodeons, and other reed-instruments of similar character, is that, if all the reeds are tuned together at the strongest pressure of the bellows, when the pressure of the bellows is diminished, the bass notes are too high in pitch for the treble, and quite loud. Attempts have been made to correct this defect, by means of an automatic connection of the swell with the bellows, but I propose, as a better means of accomplishing the same result, the employment of a device automatically controlled by the bellows-receiver, for the purpose of regulating the dip of the lower keys according to the pressure of air in the receiver, and thereby maintaining a uniform pitch throughout the scale, and enabling a more perfect *crescendo* and *diminuendo* to be effected by the bellows, leaving the swell to be operated in the usual manner; and in this device consists a part of this invention.

Another part of this invention relates to the use of two bellows, worked by separate treadles, and communicating with separate receivers, for the purpose of playing loud in one portion of the scale, and soft in the other portion, when desired, and consists in providing, between the two receivers, a communication, which can, at the pleasure of the player, either be closed, for the purpose of playing in the above-mentioned manner, or opened, to make the two receivers equivalent to a single receiver, operating alike on all the reeds.

To enable others to understand the construction and operation of my invention, I will proceed to describe it with reference to the drawings.

The receivers or wind-chests, of which there are two, are shown at A, and are separated from each other by a vertical partition, a, furnished with openings a'. Placed beside the partition a is a slide, b, provided with openings, shown in dotted outline at b', corresponding, in shape and size, with those, a', of the partition, and so situated that, when the slide is drawn outward, the orifice thereof will be brought opposite to or continuous with those of the partition a, thus causing the two receivers to communicate, or open into each other, and thus form, as it were, a single receiver, while, when the slide is pushed inward, as shown in fig. 1, the said slide, by closing the orifice of the partition a, will cause the two receivers to be wholly separated, so that they may act independently of each other. The "reed-box" of each receiver is placed at or about the part c thereof, and connected with the keys B in the usual or in any suitable manner.

Underneath each of the receivers A is an exhauster, composed of a chamber, A*, and bellows, B*, the chamber A* having its back hinged or suspended at the top, as shown at a'', and being formed with flexible or collapsible sides, in the same manner as the bellows, to permit the expansion and contraction of the same. The flat front and back of the chamber A* are pressed apart by a spring, a*, to bring the said chamber to its greatest capacity, and the front of the bellows is forced back, to contract the same, by a similar spring, b*. Extending from the upper part of the front of each bellows is a cord, c*, which, passing over a pulley, d', has its opposite end attached to a pedal, d, in such manner that, by pressing downward the said pedal, the bellows will have its front drawn forward, to expand the said bellows, as will hereinafter more fully appear.

The bellows of each exhauster communicates with the chamber A* thereof, by suitable orifices, b', formed in the front of the aforesaid chamber, or, in other words, in the partition between the bellows and the chamber, as shown in fig. 1, the said orifices being provided, at the front side of such partition, with a flexible valve, e, the valve-holes d', in the front of the bellows, being furnished, of course, with the same or equivalent valves. Each of the chambers A* communicates with the receiver A, above it, by means of a passage, e.

The slide b being drawn outward, the two receivers are wholly separated thereby, as hereinbefore explained, and the bellows being operated by the pedals, to withdraw the air from the chambers A*, and, consequently, from the receiver A, the keys belonging to the reeds of each receiver may be operated irrespective of those of

the other, to make the note produced thereby softer or louder, as the case may be, the two receivers, and the parts connected therewith, being operated independently of each other, so that the notes from the reeds of the two receivers may be made to differ in loudness, to any required degree, at the will of the player; but when it is desired that the reeds of both receivers should be of the same loudness, the slide is pushed inward, to open communication between the two receivers, thus practically causing them to constitute a single receiver, so that the same pressure will be exerted upon all the reeds, and the notes produced by the said reeds will be uniformly loud.

Attached to the upper end of the hinged or vibrating back of each chamber A*, is an inwardly-projecting spur, shown in red outline at D*, in fig. 1, upon the extremity of which rests a vertically-sliding rod, E*, the upper end of which is situated under one arm of a lever, shown at F*, the opposite arm of which extends underneath the outer-end portion of a lever, G, situated longitudinally at and above the front of the left-hand receiver, and pivoted at or near the centre of the key-board, as represented more fully in fig. 2, the pivot being indicated at e', the said lever being situated underneath the forward or free extremities of the keys I, placed above one of the receivers, so that, when the said keys are depressed, they will strike the same. A small spring, a*, placed under the forward arm of the lever F*, tends to force upward the said arm, and, consequently, the lever G, when the air is exhausted from the adjacent chamber A* by the action of the bellows connected therewith, as hereinbefore explained, the swinging back of such chamber being drawn inward to a distance proportioned to the degree of such exhaustion, whereupon the upward movement of the extremity of the spur D raises, to a proportionate extent, the sliding rod E*, the action of which, by depressing the forward arm of the lever F*, lowers the lever G, the inclination of the upper surface of which is thus diminished in a degree corresponding to that of the exhaustion of the air from the chamber A*, or, what amounts to the same thing, from the receiver, and the object of which may be thus explained:

It is found that, in varying the pressure of the air upon different reeds—for instance, upon one of the lower bass and one of the treble—tuned at the strongest pressure ordinarily employed thereon, the decrease in the pressure will cause them to become discordant, the bass notes being then too high in pitch for the treble, and quite loud.

Now, then, inasmuch as the exhaustion of air from the left-hand receiver, or that by which the reeds producing the bass notes are operated, causes, as just described, a corresponding lowering of the lever G, and, as a consequence, enables the bass-keys to be depressed to a greater extent than would be the case if the exhaustion of air from the receiver were less complete, this change in the "dip" or depression of the bass-keys causes or enables them to keep notes in perfect accord with the treble notes, and thus overcomes the varying tendency hereinbefore set forth, the movement of the back of the chamber A*, connected with the bass notes, produced by the exhaustion of air from the said chamber, acting, as it moves, to automatically limit the movement of the bass-keys, in such manner as to secure uniformity between such bass notes and those of the treble at all degrees of pressure upon the reeds, or, in other words, of exhaustion from the receivers.

What I claim as my invention, and desire to secure by Letters Patent, is—

1. Graduating the dip or depression of the keys, by mechanism controlled by the receiver, substantially such as herein described, for the purposes specified.
2. The two receivers A, and the two exhausters, with their operating-pedals, so combined that the aforesaid receivers may be worked, either together or separately, at the pleasure of the player, substantially as herein set forth.
3. The slide b, or equivalent device, arranged in such relation with the two receivers that the latter may be either separated or made to communicate with each other, substantially as and for the purpose herein set forth.
